UNITED STATES PATENT OFFICE.

ALBERT SCHMID, OF ZURICH, SWITZERLAND.

FLUID-METER.

SPECIFICATION forming part of Letters Patent No. 288,869, dated November 20, 1883.

Application filed May 10, 1883. (Model.) Patented in France March 13, 1882, No. 146,592; in Belgium May 15, 1882, No. 57,741; in Austria July 12, 1882, No. 13,772; in England August 17, 1882, No. 3,937; in Germany December 9, 1882, No. 18,848; in Spain February 15, 1883, and in Italy February 17, 1883, No. 15,103.

To all whom it may concern:

Be it known that I, ALBERT SCHMID, of Zurich, in the canton of Zurich, Switzerland, have invented certain new and useful Improvements in Fluid-Meters; and I do hereby declare that the following is a full and exact description of the invention, reference being had to the accompanying drawings, and to the letters of reference marked thereon, making a part of this specification.

My invention relates to fluid-meters for measuring and indicating the flow of any fluid under pressure, and which may serve as a motor.

It consists of two parallel cylinders, the middle portion of each of which is connected by four independent conduits with the two ends of the opposite cylinder, respectively, and with the feed-pipe and exhaust-pipe of the machine, the four separate conduit-ports at the center of the cylinder being formed in a common plane perpendicular to its axis. Each cylinder is fitted with a piston of peculiar construction, described hereinafter, adjusted to work back and forth past the central ports therein, and to serve thereby each as a cut-off for the opposite cylinder and piston. The piston-rods from the two cylinders are connected to a common crank-shaft at an angle of ninety degrees each with the other, to avoid a dead-center therein, and this shaft operates the index-hand of a counter adapted to indicate the number of its revolutions, and thereby the strokes of the pistons. In the operation of the engine the fluid has to pass through one piston before it reaches the other, which is then moved by the pressure of said fluid.

In the accompanying drawings, Figure 1 is a vertical section of the apparatus; Fig. 2, a top view in horizontal section on the line *w* *w* of Fig. 1, the section through each piston *L* *L'* being, however, taken in line 13 13 of Fig. 4, to illustrate the relation of the ports therein to the ports in the cylinder when they are brought into juxtaposition. Fig. 3 is a central vertical section, at right angles to the section in Fig. 1, through one of the cylinders. Fig. 4 is a longitudinal section, and Figs. 5 and 6 are respectively cross-sections, of one

of the pistons. Figs. 7, 8, and 9 are respectively vertical sections of the working parts of the meter through 14 14, 15 15, and 16 16 of Fig. 10, drawn to illustrate more fully the construction and operation thereof. Fig. 10 is a section through 17 17 of Fig. 7. Fig. 11 is a vertical transverse section through 18 18 of Fig. 7. Fig. 12 is an elevation of the piston, and Figs. 13, 14, and 15 are cross-sections illustrating fully its construction.

As will be readily seen the one essential feature of the meter is the peculiar construction and position of its ports and connecting passages and of the slide or cut-off valves adapted thereto, the valve controlling the feed and exhaust ports of the one cylinder being formed in the middle portion of the piston of the opposite cylinder.

The meter is preferably constructed as shown in Figs. 1, 2, and 3. It consists of a central casing or body, *A*, open at each end, and within which are formed seats for the two parallel cylinders *D* *D*, which are firmly fitted and secured therein. Each cylinder is pierced centrally with four equal ports in a common plane at right angles to its axis, said ports being designated in the drawings by the letters *b* *b'* *G* *G''* on the one piston and *b* *b'* *G* *G''* on the other. (See Figs. 2 and 10.) The two inner ports, *b* *b'*, of each cylinder are connected, respectively, with the upper and lower end of the opposite cylinder by independent passages *c* *c'* *c''* *c'''*, formed longitudinally and diagonally in the casting *A* between the cylinders. The two outer ports, *G* *G''* or *G* *G'''*, in each communicate directly the one with the feed or supply pipe *F* and the other with the exhaust or discharge pipe *F'* of the meter by means of exterior passages, *E* *E'*, formed in the body of the casting, and to which the feed and exhaust-pipes are connected by suitable couplings. The body *A* rests upon a base-plate, *I*, which is recessed on its inner face, as shown at *J*, to establish a connection between the lower end of each cylinder and the diagonal conduit leading thence to the central port, *b'*, in the opposite cylinder. The base-plate is firmly bolted to the body *A* and the joints made tight by suitable packing. By its re-

moval the interior of the meter will be exposed for inspection and repair. The cover K is formed of a hollow casting constructed with a central partition, d, dividing it into 5 chambers e e, one over each cylinder. A central bearing is bored through the partition to form the journal-box of a crank-shaft, f, adapted to revolve therein at right angles to the axis of the cylinders, so that the cranks g 10, formed upon the shaft on either side of its central journal, will be in line with the axes of the two cylinders. These cranks are set at an angle of ninety degrees each with the other to avoid a dead-point in rotating the shaft. 15 Openings are made in the ends of the cover in line with the shaft. In one of these is fitted a journal-box, k, through which is led a shaft, h, which operates the index of a counter, l. The opposite opening is closed by a screw 20 cap or plug, p. An oiling-aperture, i, is formed in the top of the cover to connect with the bearings of the shaft f for its lubrication. Within the cylinders are fitted the sliding pistons L L'. These pistons are elongated and 25 the central portion in each left solid to act as a cut-off valve to close the four lateral ports in the middle of the cylinder in passing over the same. Each piston is perforated transversely with four independent ports or 30 passages, two of them, m m, pierced diametrically through one end of the piston at right angles to each other, one above the other, on one side of the solid central portion, which serves as a valve-face, and the other two, n n, parallel 35 to each other in the other end of the piston, so that when the one end of the piston is opposite the four ports in the cylinder the passages communicating with the two ends of the opposite cylinder are connected the one with 40 the exhaust-port and the other into the supply-port diametrically opposite, and when the other end of the piston is brought into register with said openings the connection is changed, so that the passage which was 45 connected with the opposite supply-port is now connected with the adjacent exhaust-port, and that which was connected with the exhaust is now connected with the supply; hence the connection of the two ends 50 of each cylinder with the supply and exhaust pipes, respectively, is automatically cut-off and reversed at each stroke of the piston in the opposite cylinder. This movement of the apparatus is illustrated in Figs. 7, 8, 9, and 55 10, in which one of the pistons, L, is shown at the end of its downstroke and the opposite piston, L', consequently at the middle of its stroke. In this position the fluid admitted 60 from the supply-pipe F, passing into the passage E, will flow through the port G' in the cylinder D (see Fig. 8) and through the diagonal or diametric port m in the upper end of the piston L, and will pass down through the passage or conduit e into the lower end of 65 the opposite cylinder, D', to act against the piston L' therein and force it up. At the same time connection is established through the

second diagonal diametric port m in the piston L, between the upper diagonal conduit e', communicating with the upper end of the cylinder D' and the exhaust-passage E' and pipe F'. In the meantime the central valve portion of the piston L', covering the four lateral ports in the middle of the cylinder D', closes for the moment all connection between the cylinders D and the inlet and exhaust ports. The upward movement of the piston L' will, however, immediately open the ports, and, bringing the transverse parallel passages in the lower end of the piston into register with the inlet-port G and conduit e'' on the one side and the exhaust-port G'' and conduit e''' on the other, will thus establish communication through these passages between the supply-pipe F and the lower end of the cylinder D 85 and the exhaust-pipe and the upper end of the same cylinder. The piston L' therein will consequently move upward, and in so doing will operate at mid-stroke to cut off and then reverse the communication of the inlet and 90 exhaust ports with the opposite cylinder, D', when the piston L' therein has reached the end of its upward stroke, so that by means of the parallel passages n in the lower end of the piston L' the inlet-port will be connected with 95 the upper end of the cylinder D' through the upper conduit, e', and the exhaust with its lower end through the lower conduit, e, and the movement of the piston L' be thereby reversed. The two pistons thus act each as a 100 cut-off or slide valve for the other, and being connected with the shaft f by the cranks g g, which work at an angle of ninety degrees each with the other, the motion of the piston and shaft will be continuous and uniform. The 105 diameter of each cylinder and length of stroke being known, each revolution of the crank-shaft f will represent the passage through the meter of a known quantity of fluid, which will be accurately registered by the index-counter 110 l, properly graduated and adjusted for this purpose. The same apparatus may be used as a pump or motor by prolonging the shaft f outwardly through a stuffing-box to carry a driving-pulley. 115

I claim as my invention—

1. The combination, in a fluid meter or motor, with a common crank-shaft and with suitable pistons actuating said shaft, of two parallel cylinders traversed by said pistons, each provided with four lateral ports midway in the length thereof adapted to be lapped and closed simultaneously by the center of its piston, and to communicate, respectively, each independently by suitable connecting-passages with the top and bottom of the opposite cylinder and with the supply and exhaust ports of the meter, all substantially in the manner and for the purpose herein set forth. 125

2. The combination, in a fluid meter or motor, with parallel cylinders, each provided midway of its length with four lateral ports adapted to be closed simultaneously by the 130

central portion of the piston moving therein, and with a common crank-shaft at right angles to said cylinders, of two pistons, each fitted in one of said cylinders, and constructed 5 with a central solid portion adapted to lap and close as a valve the lateral ports in the cylinder, and with two parallel transverse passages on one side of the central valve, and two transverse diametric passages formed at right 10 angles to each other, one above the other on the other side of the central valve, each passage adapted to establish in turn, in the movement of the piston, communication through the piston between the opposite central lateral ports in the cylinder, substantially in the 15 manner and for the purpose herein set forth.

3. The combination, in a fluid meter or motor, of the body A, the two parallel piston-cylinders or working-chambers D D' therein,

the lateral ports b and connecting-passages c 20 in and between the cylinders, the base or bed plate I, supporting the body, the cover K, the central journal-bearing, d, dividing the cover interiorly into two chambers above the cylinders, the crank-shaft f, rotating within the 25 cover, the indicating-shaft and counter l, and the pistons L L', constructed with transverse passages m n on either side of a central valve-surface, all combined and connected substantially in the manner and for the purpose here- 30 in set forth.

In testimony whereof I have signed my name to this specification in the presence of two subscribing witnesses.

ALBERT SCHMID.
